UNITED STATES PATENT OFFICE

WILLIAM A. EDWARDS, OF CHICAGO, ILLINOIS

CARBURETOR

Application filed February 12, 1925. Serial No. 8,704.

The purpose of this invention is to provide an improved construction of a fuel mixture forming device for internal combustion engines particularly adapted for installation in connection with the engine of an automotive vehicle. It consists in the elements and features of construction shown and described as indicated in the claims.

In the drawings:—

- 10 Figure 1 is a diagrammatic view showing in dotted line the chassis and engine of an automotive vehicle and in full line in side elevation, a structure embodying this invention installed on the chassis in the relation to the fuel supply tank, engine, and fuel mixture conduit contemplated by the construction of said device.
- 15 Figure 2 is a section at the line 2—2 on Figure 3.
- 20 Figure 3 is a section at the line 3—3 on Figure 2.

Figure 4 is a sectional view similar to Figure 2 showing a detail modification of the mixture forming device.

25 Figure 5 is an enlarged detail of a portion of Figure 4, being a section in the same plane as Figure 4.

Figure 6 is a section at the line 6—6 on Figure 5.

30 Figure 7 is a horizontal detail section at the line 7—7 on Figure 3.

Figure 8 is a detail of a portion of Figure 3 on a large scale.

35 In the structure shown in the drawings it will be understood that the engine is indicated in dotted line at A, A¹ being the intake manifold; that the fuel mixture conduit leading to the engine is indicated in dotted line at B, (a heating jacket not concerned in this invention being shown in dotted line at C). The main fuel supply tank is shown at 10, mounted in the customary position at the rear of the chassis and connected by a pipe, 11, with a level-governing chamber or float bowl, 12, wherein the governed level is indicated by dotted line, m, the level-governing float being shown at 13 controlling the inlet valve, 14, all according to familiar construction of carburetor float bowls and the like. A horizontal portion of the fuel mixture conduit, B,

is shown at 15, formed integrally with the float bowl and extending cross-wise of the vehicle in the installation as illustrated. In this horizontal portion of the fuel mixture conduit in the form of the invention shown in Figures 2 and 3, there are provided a plurality of Venturi bushings or sleeves (two being shown, but any larger number being within the scope of the invention) these venturis being desirably positioned in fairly close succession in the fuel mixture pipe, and being,—preferably for the specific purpose for which they are provided,—in plurality, constricted to different degrees, the least constricted being first in order from the level-governing chamber, and subsequent venturis being successively more and more constricted, that is, having their diameters at the apex of the constriction successively less and less from the first in the path of movement of the fuel mixture through the conduit to the last in order. For receiving these Venturi sleeves or bushings, 20 and 21, the fuel mixture pipe section, 15, is bored and the Venturi sleeves are fitted to the bore not so as to require drive fit, but so that they can be readily positioned without substantial leakage around them in said section, 15, being secured in position as hereinafter described. From the lower part of the level-governing chamber or float bowl, 12, a fuel duct, 16, leads out through the stem, 17, which projects from the intersection of the stem and cross member of a T-shaped boss, 18, 19, at right angles to both said stem and cross member, said boss being formed integrally with the float bowl, and from the intersection of the members, 18 and 19, of the boss, a vertical branch, 18, extends for making junction with the integral fuel mixture conduit member or section 15. To produce a duct, 19^a, the horizontal element, 19, of the cross-shaped boss is bored from end to end, intersecting the bore which forms the duct, 16, in the member, 17, of the boss leading from the float bowl, that bore, 16, being made from the outer end of the radially protruding stem, 17, of the boss, the outer end being threaded and permanently closed by a plug, 23. The bore in the vertical branch, 18, of the boss

100

is counterbored from the lower end as seen at 25, forming a counter-sunk shoulder, 25^a, and this counterbore is further counterbored as seen at 26, and the final portion of the 5 original bore at its entrance into the cavity of the fuel conduit section 15 is threaded to receive a bushing, 27, said bushing being reduced in diameter and threaded toward the end for engaging the thread of the original 10 bore and forming a shoulder for seating at the shoulder, 25^a. This bushing is axially bored from end to end and counterbored from its lower end to form a needle valve seat, 27^a back of the discharge end of said bushing. 15 The Venturi bushing or sleeve, 21, has a radial bore from one side opening at the constriction of the Venturi passage, this radial bore being positioned and diametered for protrusion thereinto of the end of the bushing, 27, 20 which has the thread stripped from it for a distance equal to the thickness of the Venturi sleeve wall at that point, the bore in the Venturi sleeve into which the bushing protrudes being diametered for snug fit of the stripped 25 end of the bushing, 27. The lower end of the vertical branch, 18, of the boss below the horizontal elements 17 and 19 is threaded to receive a bushing, 30, screwed thereto and having a shoulder at 31 for stopping and 30 seating leak-tight on the lower end of the boss. This bushing is threaded for engagement of the threaded stem, 40, of a needle valve, 41, which seats at the valve seat described in the upper end of the bushing, 27, 35 and is provided at its lower end with a suitable head, 42, for manual operation, a stuffing box, 43, being provided on the reduced lower end of the bushing, 30, to prevent any leakage through the thread of the valve stem. The 40 horizontal boss member, 19, bored from end to end as stated is counterbored from the right hand end, referring to Figure 2, nearly to the other end, to form a valve seat at 19^a, and threaded at the first mentioned end for 45 engagement with the threaded portion, 22^a, of the stem of a valve, 22, a stuffing box, 23, being provided at the first mentioned end, and a pipe, 50, being connected by a compressible coupling, 51, at the other end beyond the valve seat. The pipe, 50, extends 50 up across and past the section, 15, of the fuel mixture conduit integral with the float bowl, between said float bowl and said integral conduit section, and is coupled by compressible 55 couplings, 55, with an elbow fitting, 56, which is screwed into the upper side of the fuel conduit section, 15, said elbow having a shoulder, 57, for stopping it leak-tight against said section, 15, and extending from said shoulder 60 with sufficient length to enter a counter-sink at 20^a around a port, 20^b, discharging in the Venturi throat at the apex of the constriction thereof. It will be understood that the elbow fitting thus serves as a key to position and 65 secure the venturi, 20, in place in the fuel

mixture conduit section, 15, as the bushing, 27, serves to position and secure the venturi, 21.

In Figures 4, 5 and 6 there is shown a modification consisting in employing a single 70 Venturi sleeve or bushing instead of a plurality of such Venturi bushings shown in the preceding figures. In this modification the single Venturi sleeve, 60, has a peripheral groove, 61, encompassing the sleeve at the 75 point of greatest constriction, its width extending longitudinally of the sleeve a short distance both ways from the transaxial plane of the apex of the constriction; and at one side an aperture is made leading radially into 80 the cavity of the bushing substantially at the transaxial plane of the apex of the constriction through which protrudes the reduced terminal nipple, 63^a, of a bushing, 63, having an axial bore, 63^b, said bushing being inserted in the bore of a hollow boss, 15^m, protruding downward from the boss forming the horizontal section, 15, of the fuel mixture conduit. The bore for inserting the bushing, 63, in the boss, 15^m, is closed at the lower end 85 by a plug, 15ⁿ, and this boss has a laterally protruding axially apertured boss, 15^p, for coupling thereto one end of a pipe, 65, the other end of which is similarly coupled to the end of the horizontal member, 17^x, of a 90 cross-formed boss corresponding to the boss, 17, 19, of the form shown in Figure 3, which horizontal member, 17^x, and the stem 19^x, of said boss are bored to provide a duct for conducting the fuel from the float bowl by way 95 of the pipe, 65, for discharge through the nipple, 63^a, of the bushing, 63. In this form the horizontal boss member, 17^x, is bored and counterbored and provided with needle valve and stuffing box identical in form and construction with the corresponding feature shown and described in Figure 2. It will be understood that in this form the connection leading laterally from the stem, 19, of the cross-shaped boss of the form shown in Figure 3 by way of the pipe, 26, is omitted. In this modification the single Venturi bushing or sleeve, 60, has a second aperture, 61^a, for fuel discharge bored radially from the 100 peripheral groove, 61, into the cavity of the 105 Venturi bushing, at a position diametrically opposite that at which the nipple, 63^a, discharges. 110

Upon considering the structure above described it may be understood that the liquid fuel will be drawn from the level-governing chamber or float bowl and discharged into the fuel mixture conduit by virtue of the sub-atmospheric pressure induced at the point of discharge into said conduit by the 115 velocity of air flow through the conduit at said point of discharge which is in the vicinity of the flow-accelerating restriction furnished by the Venturi sleeve or bushing. It will be seen that a certain minimum ve- 120 125 130

lacity of air flow will be necessary to take a minimum quantity of fuel from the lowest discharge port,—as 27^a in the venturi, 21, of the forms shown in Figures 2 and 3, or 5 the nipple, 63^a, of the forms shown in Figures 4, 5 and 6; and that a higher velocity of air flow will take fuel from the discharge located at the higher level, viz, the port, 20^b, in the venturi, 20, of the forms shown in 10 Figures 2 and 3 or the port, 61, in the venturi, 60, of the forms shown in Figures 4, 5 and 6. It may now be understood that the purpose of the invention is to cause the engine when running idle with the throttle 15 valve nearly closed and thereby drawing a minimum quantity of air at a minimum velocity through the venturi or venturis, to take only the minimum quantity of fuel necessary to develop the energy sufficient 20 for operating the engine at idling speed without load, and upon opening the throttle for increasing the engine speed and operating it under load the increased velocity of air flow through the fuel mixture conduit will not 25 only automatically increase the amount of fuel drawn through the lower discharge at the Venturi constriction, but also will cause additional fuel discharge at the more elevated port whether in the same venturi as 30 in the forms shown in Figures 4, 5 and 6, or at a separate venturi located at another point in the fuel mixture conduit.

Since the air velocity through the venturi with any given engine speed and throttle 33 opening will be greater as the restriction is greater,—that is, making cross-section of the air path at the point of constriction less,—there is an advantage in pluralizing the Venturi sleeves or bushings, as compared with 40 using only a single Venturi sleeve with the fuel discharges respectively at the upper and lower sides thereof, because with a plurality of venturis, the venturi which has the fuel discharge into it at the higher point, as at 45 the upper side, may also have its throat opening greater, that is, less restricted, so that at the point at which greater air velocity is necessary to produce liquid flow, higher speed of the engine and wider opening 50 of throttle, may be necessary to produce a given velocity of air flow. From the foregoing it will be understood that in any given construction of venturi and position of the fuel discharge port therein, the ratio of fuel 55 flow to engine speed and resulting air flow first rises from a minimum, beginning when the air depression at the point of fuel discharge into the venturi becomes sufficient to lift the fuel to that point, up to the stage 60 at which fuel is lifted sufficiently to keep the fuel passage full and the friction of fuel flow reaches a certain degree; and then, as the engine speed increases and the increasing air friction through the venturi causes 65 retardment of the air flow, this retardment

gradually causes the ratio of fuel to the air to decline. From this it results that when there is provided only one fuel discharge, which is therefore in only one unchanging relation to one and the same venturi, the maximum work per unit of fuel consumed is obtained only at one stage of operating conditions in respect to engine speed and load, and at any lower or higher speed and load the amount of work derived from a unit of fuel is below the maximum. The construction described tends to obviate this defect by the arrangements of the several fuel discharges in relation to the venturi or venturis into which they all respectively discharge; so that decline of fuel supply ratio to air supply at one discharge overlaps increase in such ratio at another fuel discharge. 70 When employing this means for the purpose indicated it will be seen that the range 75 of engine speed and throttle opening between those which produce fuel discharge at the venturi having the lower discharge, and those which begin to produce fuel discharge at the venturi having the fuel discharge at the higher level, may be much wider than if the two fuel discharges were into the same venturi, or in two venturis having the same constriction. 80

The importance of the provision shown for 85 causing increase of liquid fuel supplied at a certain stage in the increase of engine speed and consequent increase of air velocity, notwithstanding the fact that the mere increase 90 of air velocity tends to cause increase of fuel flow through the same discharge from the same source, arises from the fact, ascertained by critical observation of internal combustion engine operation, that with any given venturi or other form of flow-accelerating restriction 95 in the fuel mixture conduit, the rate of increase of liquid fuel discharge, resultant 100 from increased air velocity through the venturi, diminishes from a certain point, that is to say, nearly a maximum of fuel discharge 105 is reached and the fuel discharge is not substantially increased thereafter by the further increase of velocity of air flow. Whatever be the cause of this phenomenon, (sometimes attributed to "skin friction" increasing faster 110 than the air velocity increases), it is important to provide means for continuing the increase of fuel content in the fuel mixture 115 after the air velocity has passed the point at which it causes an increase in the fuel supply derived through a single duct; and the present invention provides means for accomplishing this purpose. 120

I claim:—

1. A fuel mixture forming and feeding apparatus having in combination with a fuel mixture conduit, an initial air inlet, a governed level fuel chamber and fuel flow connections therefrom to said conduit, said conduit having varying cross sectional areas. 125

causing varying flow capacity at different portions of its length subsequent to said initial air inlet and antecedent to any additional air inlet, said conduit having openings communicating with said fuel flow connections for fuel discharge in the conduit arranged successively at the localities of said varying cross section and flow capacity, said fuel openings being fixedly positioned at the respective cross sectional areas, the discharge at any cross section of larger area being at higher level than the discharge at a cross section of lesser area, for causing the decline of the ratio of fuel to air at one of said openings 10 to overlap in time of occurrence the rise of ratio at another of said openings.

2. A fuel mixture forming and feeding apparatus having in combination with a fuel mixture conduit having an initial air inlet, a governed level fuel chamber and fuel flow connections therefrom to the fuel mixture conduit subsequent to said initial air inlet, said conduit having a plurality of permanent constrictions, reducing it in cross section in different degree for causing different acceleration of air flow at said constricted portions respectively, located in the conduit antecedent to any additional air inlet thereto, successively and in such manner that the entire air flow derived from the initial air inlet passes through all of said constricted portions in the order of their successive arrangement; said fuel flow connection having openings for fuel discharge in the conduit antecedent to any additional air inlet and in-co-operative relation to said constrictions respectively, said openings being located relatively to the respective constrictions differently in respect to the areas of lowered pressure due to said respective constrictions, and differently in respect to the levels of said openings relative to the governed level of the fuel chamber an opening at a constriction which reduces the cross section of the conduit 20 in greater degree being at lower level, and an opening at a constriction reducing the cross section of the conduit in lesser degree being at higher level.

3. A fuel mixture forming and feeding apparatus having in combination with a fuel mixture conduit having an initial air inlet, a governed level fuel chamber and fuel flow connections therefrom to the fuel mixture conduit subsequent to said initial air inlet, said conduit having a plurality of permanent constrictions reducing it in cross section for causing acceleration of air flow at said constricted portions in the order of their successive arrangement, said constrictions differing 30 in the degree to which they reduce the cross section of the air path at the points at which they are located, said fuel flow connection having a plurality of openings for fuel discharge in the conduit antecedent to any additional air inlet corresponding to the plu-

rality of constrictions, and located in substantially the same relations longitudinally of the conduit to the constrictions respectively; whereby the amounts of fuel flow at the different openings are functions of the degrees of restriction at said openings respectively. 70

4. A fuel mixture forming and feeding apparatus having in combination with a fuel mixture conduit having an initial air inlet, a governed level fuel chamber and fuel flow connections therefrom to the fuel mixture conduit subsequent to said initial air inlet, said conduit having a plurality of permanent constrictions reducing it in cross section for causing acceleration of air flow at said constricted portions, located in the conduit antecedent to any additional air inlet thereto, successively and in such manner that the entire air flow derived from the initial air inlet passes through all of said constricted portions, in the order of their successive arrangement, said constrictions differing in the degree to which they reduce the cross section of the air path at the points at which they are located, said fuel flow connection having a plurality of openings for fuel discharge in the conduit antecedent to any additional air inlet corresponding to the plurality of constrictions and within the extent of said constrictions respectively, said fuel discharge 80 openings being at different levels with relation to the governed level of the fuel chamber. 85

5. A fuel mixture forming and feeding apparatus having in combination with a fuel mixture conduit having an initial air inlet, a governed level fuel chamber and fuel flow connections therefrom to the fuel mixture conduit subsequent to said initial air inlet, said conduit having a plurality of permanent constrictions reducing it in cross section for causing acceleration of air flow at said constricted portions, located in the conduit antecedent to any additional air inlet thereto, successively and in such manner that the entire air flow derived from the initial air inlet passes through all of said constricted portions in the order of their successive arrangement, said constrictions differing in the degree to which they reduce the cross section of the air path at the points at which they are located, said fuel flow connection having a plurality of openings for fuel discharge in the conduit antecedent to any additional air inlet corresponding to the plurality of constrictions respectively, said fuel discharge 95 openings being at different levels with relation to the governed level of the fuel chamber. 95

100

105

110

115

120

123

125

6. A fuel mixture forming and feeding apparatus having in combination with a fuel

mixture conduit having an initial air inlet, a governed level fuel chamber and fuel flow connections therefrom to the fuel mixture conduit subsequent to said initial air inlet, 5 said conduit having a plurality of permanent constrictions reducing it in cross section for causing acceleration of air flow at said constricted portions, located in the conduit antecedent to any additional air inlet thereto, 10 successively and in such manner that the entire air flow derived from the initial air inlet passes through all of said constricted portions in the order of their successive arrangement, said constrictions differing in the degree to which they reduce the cross section 15 of the air path at the points at which they are located, said fuel flow connection having a plurality of openings for fuel discharge in the conduit antecedent to any additional air 20 inlet corresponding in number to the plurality of constrictions, and the fuel discharge openings being at different levels with relation to the governed level of the fuel chamber in the several constrictions respectively, 25 the opening co-operating with the least constriction being at the highest level, and any opening co-operating with a greater constriction being at correspondingly lower level, the fuel mixture conduit being substantially horizontal 30 at the location of the successive constrictions therein, and the fuel discharge openings being respectively at the lower and upper sides of said horizontal portion of the conduit whereby, regardless of the longitudinal 35 separation of the constrictions, the fuel discharge openings may be similarly related longitudinally of the conduit to the respective constructions without differing in level more than the diameter of the conduit.

40 7. The construction defined in claim 6, the fuel mixture conduit having the horizontal portion comprising the successive constrictions, formed integrally with the governed level fuel chamber, the fuel discharges being 45 by means of ducts formed in said integral structure leading from the fuel chamber for discharge respectively at the lower and upper sides of the conduit proximate to the respective constrictions.

50 In testimony whereof, I have hereunto set my hand at Chicago, Illinois, this 6 day of February, 1924.

WILLIAM A. EDWARDS.
